W. H. CATER

WELL SCREEN

Filed Sept. 16, 1921

UNITED STATES PATENT OFFICE.

WILLIAM H. CATER, OF CHICAGO, ILLINOIS.

WELL SCREEN.

Application filed September 16, 1921. Serial No. 501,190.

To all whom it may concern:

Be it known that I, WILLIAM H. CATER, a citizen of the United States, and resident of Chicago, in the county of Cook and 5 State of Illinois, have invented certain new and useful Improvements in Well Screens, of which the following is a specification.

My invention pertains to apertured or 10 perforated well-screens or casings and similar structures designed to be driven or forced down into the ground as the wells are sunk and to permit water or other liquids to flow through the holes in their sides.

15 One object of the new and improved form of structure is to make the sheet-metal screen or casing of substantially uniform strength throughout its length, whereby no part or section is weaker than any other, 20 and hence not more likely to give way, crush, or rupture under the rather severe strains and stresses to which it is subjected.

A further purpose of the invention is the 25 provision of a foraminous sheet-metal shell or casing which is easier to force down into the earth than those types of reticulated screens in more common use.

An added object of the new style of perforated screen or casing is the easier access of 30 liquids to its slots or openings.

Another aim of the invention is the production of a screen or casing of this form which possesses greater than the customary strength throughout, hence, in some cases 35 permitting the employment of a thinner gauge of metal than has heretofore been usual.

Still another advantage accruing from the employment of the new screen or casing 40 is the certainty of making connection with any water or other liquid vein, no matter how narrow or shallow it may be.

One more benefit arising from the use of 45 the present invention in practical physical embodiment resides in having the bottom shoe or foot of the casing or screen and the coupling members which unite its sections together bear at their ends against the outwardly-bowed metal strips which provide 50 between their edges and the main body of the shell the required slots or openings, thus giving to the structure as a whole an unusual degree of strength and power to 55 successfully withstand the severe strains to which the casing is put during the well-sinking operation.

In order that those skilled in this art may have a full and complete understanding of the invention and the various structural and functional advantages accruing from its 60 use, in the accompanying drawing forming a part of this specification, and to which reference should be had in connection with the following detailed description, I have illustrated a desirable and preferred embodiment of the invention, like reference characters referring to the same parts throughout the several views.

In this drawing:

Figure 1 is a vertical, central section 70 through the well-casing and its shoe and the enclosed associated pump;

Figure 2 is a horizontal section on line 2—2 of Figure 1; and

Figure 3 is a fragmentary elevation on an 75 enlarged scale of a portion of the exterior of the screen or casing:

By reference to the drawing, it will be seen that the perforated or apertured sheet-metal screen or casing, as is usual, is composed of a series of tubular sections or parts 80 11 arranged end to end in axial alignment, such elements being fastened together, as is customary, by suitable coupling-rings 12, secured to and encasing the unslotted end portions of the casing sections or units. 85

Each such sheet-metal cylindrical section is provided with many horizontal circular rows of slots or elongated holes 13, those of each horizontal row being offset sidewise 90 from those of the rows directly above and below it a distance equal to one-half the space between adjacent slots of the same row.

Stated somewhat differently, the slots of 95 the rows are staggered, those of each row being opposite the unperforated portions of the metal band or section either above or below it.

It is to be noted, also, however, that each 100 slot extends upwardly beyond the aligned lower ends of the slots of the next row above it and continues down below the registered upper ends of the slots of the row beneath it.

105 All of these numerous slots or elongated openings, which from another viewpoint are arranged in staggered longitudinal rows, are formed by shearing the metal along spaced, parallel, vertical lines of the length of the slot to be produced and subsequently, or simultaneously with the cut-

ting operation, forcing outwardly the intervening narrow metal strip 14, substantially parallel to the face of the shell, except at its ends which join directly with the main body of the metal of the screen with which they form integral parts.

Thus, two, long, narrow slots are provided at the opposite edges of each of such outwardly-pressed, bridge portions of the 10 metal communicating directly with the elongated hole or cavity directly beneath the metal strip.

At its lower end, the casing is equipped with a flaring, sectional foot or shoe 15 composed of a plurality of longitudinal parts 15 with registering, outstanding, apertured lugs 16, 16, fastened together by securing bolts 17, 17.

The lower circular edge (18) of this foot 20 or shoe is sharp to facilitate its passage through the earth, the outer surface 19 adjacent to such edge being substantially vertical, the corresponding inner face 20 being inclined or flaring outwardly to such 25 edge.

The lower larger diameter of this foot or shoe is substantially greater than that of the couplings fastening the casing sections together, thus rendering less difficult the 30 downward movement of the whole structure through the earth.

The lower end of the lowermost screen section rests on an internal, circular shoulder 21 in the upper portion of the foot or 35 shoe, and the top edge of the latter bears against the lower ends of the lowermost row of the outwardly-displaced strips of metal which provide the slots or openings for the screen.

40 Thus a firm union between the foot and casing is secured, an end of each bearing against some portion of the other to more effectively transmit the downward thrusts with the least danger of damage to the parts.

45 In somewhat similar manner, the top and bottom edges of each coupling-ring 12 bear on the ends of the endmost rows of the outwardly-bowed bridge pieces of the casing sections, whereby to secure a strong junction 50 between the ends of the parts of the sectional screen.

These styles of connections between the shoe and couplings and casing sections also provide a smoother outside surface to the 55 structure than has heretofore been usual.

This manner of fastening the shoe to the casing and the means employed for securing together the casing sections precludes the 60 external exposure of any horizontal bands or zones of the sheet-metal forming the casing which is unperforated with the resulting advantages as specified hereafter.

The pump employed in connection with such screen or casing comprises a cylinder 22 65 which at its lower end fits over and is se-

cured to a base-ring 23 having a bottom edge notched or recessed at 24, 24 for the passage inwardly therethrough of water, earth, gravel, etc., such end element 23 within the lower part of the cylindrical shell 22 being 70 equipped with a hinged valve 25 disposed in an inclined relation when closed over the end of member 23 to facilitate its upward opening movement under the suction action to which it is subjected. 75

Internally, the pump-cylinder accommodates a reciprocating perforated or ported piston or plunger 26 mounted fixedly on the lower end of an upright rod or shaft 27 having an eye or loop 28 at its upper end 80 for the attachment of an operating cable or chain, not shown.

A round, flexible valve 29, such as of leather or rubber, is positioned over the top face of the plunger and is adapted to open 85 and close the holes or ports of the latter, depending upon the direction of movement of the parts as will be readily understood.

A coil cushion-spring 30 surrounds the rod or shaft just above the valve, as is 90 clearly indicated.

At the top end of the pump, the rod or shaft 27 slides through a bearing-block 31 swivelled at 32 in the walls of the pump-cylinder, the latter being cut away on one 95 side at 33 for a sidewise discharge of the pump's contents, during which operation the rod or shaft 27, by reason of the turning of the bearing-block, occupies a recess or slot 34 cut in the opposite side of the pump-cylinder. 100

The appliance operates substantially as follows:

Assuming that the perforated casing or lining, composed of the several united apertured sections 11, equipped at its lower end with the sharp-edged foot or shoe, has been weighted or loaded at its top end, the pump is lowered in the well and the casing until the base-ring 23 rests on the earth at the 110 bottom of the well, in which position it will be surrounded by the foot or shoe 15, piston or plunger 26 being lowered to the bottom portion of the pump shell or cylinder, the valve 25 at this time being closed. 115

Then the cable or chain, not shown, engaging the eye 28, is lifted, causing the rapid ascent of the piston or plunger, which creates a high degree of suction beneath it, thus unbalancing the air pressures, occasioning the opening of valve 25 and the filling of the pump-cylinder beneath the piston with a mixture of dirt, gravel, water, etc., owing to the fact that such substantial suction is created by the pump in the unapertured or unperforated sloping gravity foot or shoe, and it is particularly effective because the shoe or foot is without holes or inlets, in removing the earth from beneath the foot or shoe and sucking or drawing 120 125 130

the latter downwardly which action, of course, is assisted by gravity acting on the outer earth pressing down on the sloping exterior face of the shoe.

5 If the bell-shaped foot were apertured, the water in flowing inwardly through its perforations would tend to draw the surrounding earth inwardly in the same direction, which action would render no assistance in 10 the necessary and essential downward travel of the weighted casing.

Where, however, an unapertured foot or shoe is employed, as in this instance, the outside earth tends to be drawn or sucked downwardly on the outer sloping surface of the 15 shoe, by reason of the suction action present around its bottom edge, and such tendency to downward movement by reason of the suction is supplemented by the action of 20 gravity on such earth which effectively and efficiently assists in forcing the casing or lining downwardly.

Thus, it will be seen that a marked and definite advantage is had in employing an 25 unperforated foot or shoe performing the function stated.

It will be perceived, that, unlike those earlier well screens or linings having alternate horizontal bands of perforated and unapertured metal, each of the present screen 30 sections is uniformly slotted throughout its length.

During the use of such earlier casings, the earth becomes lodged against the casing in 35 more or less horizontal ribs or ridges in register with the smooth unslotted bands or portions of the screen and disposed between the adjacent top and bottom ends of the outwardly-pressed metal strips of the rows 40 directly beneath and directly above them, and the presence of these ribs or portions of earth interlocking more or less with the rough exterior surface of the casing hinders the effective downward travel thereof.

45 In the present screen, however, there are no such circular, horizontal, external grooves around the casing between circular rows of outstanding metal strips and hence there is no possibility for the presence of such rough 50 ribs or ridges with their detrimental motion retarding and obstructing the descent of the casing.

In other words, owing to the offset or 55 staggered relation of its outstanding metal strips, the new casing, as a whole, presents a much smoother exterior surface than those of the older type, and hence the present casing may be forced into the ground more easily and with less pressure.

60 It will be observed, also, that, whereas the earlier screens, with their alternate bands of perforated and unperforated metal were of unequal strength throughout their length, presenting alternate zones of strength and 65 weakness in some degree, the new screen is

of uniform strength throughout its length, and no part thereof is any more likely than any other part to crush or collapse under the strains to which it is put.

By reason of this desirable characteristic, 70 in some instances, it is possible to use a thinner gauge of sheet-metal than has heretofore been usual.

It will be noted in addition that, because of the even distribution of the outwardly bowed metal strips throughout the entire body of each screen section, it is stronger 75 against radial or circumferential inward crushing than are those sections employing such strips and their associated slots in segregated circular groups.

Also, because in the improved screen there are slots or openings throughout the entire length of each section, the water or other liquid encountered in any thin or shallow 80 vein in the earth through which the wall is being sunk is certain of access to the interior of the casing, because some of the slots are sure to be in register with the vein, regardless of its small dimensions. This, of 85 course, is not true of those screens having bands or portions of unapertured metal.

Furthermore, by staggering the slots and metal strips, that is shifting lengthwise the casing the alternate ones of each circular 90 horizontal row, in the manner clearly illustrated in the drawing, or, stated differently, shifting longitudinally of the casing the alternate lengthwise rows of metal strips and the holes formed thereby, a freer access is 95 had to all the slots because of the greater distance between them than in the earlier style of casing referred to above.

The invention is not limited and restricted to the exact details of structure shown and 100 described, because these are susceptible of more or less radical modifications without departure from the heart and essence of the invention and without the sacrifice of any 105 of its substantial benefits and advantages.

Certain features of construction shown and described herein and not claimed form the subject-matter of my United States Patent 1,431,872 issued October 10, 1922.

110 I claim:

115 1. A foraminous single-thickness sheet-metal well-screen, adapted for association with a pump inside thereof and for descent in the earth during the driving of the well, having a single-thickness sheet-metal wall 120 provided with slots arranged in longitudinal and transverse rows, each pair of slots being formed by a metal strip, integral with the body of the screen and connected therewith at its opposite ends, outwardly deflected 125 from the main body of the screen, the interior of the screen being practically smooth, the strips of each longitudinal row being offset lengthwise the screen with relation to those of the longitudinal rows on opposite 130

- sides thereof, the slots of each transverse row extending lengthwise the screen beyond the adjacent ends of the slots of the two transverse rows directly above and below it.
5. 2. A well-screen of the character described, comprising in combination a plurality of foraminous sheet-metal well-screen sections arranged in register end to end, each of said sections having slots there-
10 through provided by outwardly-deflected strips of the sheet-metal integral at their ends with the main body of the metal-sheet, and a coupling fastening adjacent sections of the screen together encircling cylindrical
15 end portions thereof and bearing at its opposite ends against the endmost outstanding strips of such sections.
3. In a well-screen of the character de-
scribed, the combination of a foraminous sheet-metal well-screen, adapted for association with a pump inside thereof and for descent in the earth during the driving of the well, having a sheet-metal wall provided with slots formed by metal-strips integral at their ends with the body of the screen and outwardly deflected therefrom, said strips and associated slots being arranged in longitudinal rows staggered with relation to those of the adjacent rows, and a shouldered flaring unperforated shoe having a sharp lower edge secured to the bottom end of said screen with the latter bearing on the shoe shoulder and the shoe bearing against the lower ends of the lowermost row of said outstanding metal strips.

WILLIAM H. CATER.
